J. M. GERAGHTY, ADMINISTRATRIX.

AUXILIARY DEVICE FOR AUTOMATIC ELECTRIC CONTROL SYSTEMS.

APPLICATION FILED JAN. 5, 1916.

1,230,150.

Patented June 19, 1917.

UNITED STATES PATENT OFFICE.

JAMES V. GERAGHTY, OF NEW YORK, N. Y.; JULIA M. GERAGHTY ADMINISTRATRIX
OF SAID JAMES V. GERAGHTY, DECEASED.

AUXILIARY DEVICE FOR AUTOMATIC ELECTRIC CONTROL SYSTEMS.

1,230,150.

Specification of Letters Patent. Patented June 19, 1917.

Application filed January 5, 1916. Serial No. 70,346.

To all whom it may concern:

Be it known that I, JAMES V. GERAGHTY, a citizen of the United States, residing in the borough of Manhattan, in the city, 5 county, and State of New York, have invented certain new and useful Improvements in Auxiliary Devices for Automatic Electric Control Systems, of which the following is a specification, reference being made to the 10 accompanying drawings, forming a part thereof.

My invention relates to automatic motor control systems, particularly for cars on an electrically operated railway, operated by 15 compressed air; and the main object of my invention, among other things, is the provision of novel means for operating the magnet valves, at the will of the motor-man, which valves cause the main control cylinder 20 drum to advance or rotate automatically, when such control cylinder fails to so advance for any reason during the ordinary operation of the car.

In ordinary surface electric railway practice, where pneumatically operated control systems are employed, frequent difficulties are experienced in operating the motor through the inability of the motor-man to 25 actuate the valves or magnets which control the rotation of the main controller shaft and drum. Such difficulties may arise when the car is on a grade greater than that for which the control is adjusted for normal operation; again when the car is pushing one or 30 more cars, or when one of the motors on the car becomes disabled, or inefficient for any cause; also when the magnets for the valves leak or become sluggish, or when the main control cylinder sticks because of too much 35 tension of the fingers, or from defective bearings or from any other mechanical defect. Furthermore such difficulties may occur when the main control cylinder is prevented from advancing on account of a defective limit switch. Such magnet valves of 40 an automatic motor control system may be operated by pressing down the ends projecting above the magnets, but in order to accomplish this movement, it is usually necessary to remove the hood; since the main controller is almost invariably located beneath the floor of the car, or in some other 45

inaccessible place, this movement of the projecting valve ends cannot be accomplished when, for any reason, the car becomes stalled 55 on the highway or street.

The characteristic feature of my improved device is, therefore, the provision of a simple and efficient mechanism whereby the magnet valves may be positively actuated at all 60 times and under all conditions, at the will of the operator; my auxiliary device renders the advance or rotation of the main control cylinder entirely under the will of the motor-man, and is particularly useful in varied 65 emergencies that so continuously arise in the operation of an electrically operated railway system.

In the accompanying drawings, I have two forms or embodiments of my invention, 70 as applied to a main controller known as the "Westinghouse PK control," in which Figure 1 shows a side elevation view, partly in cross-section, of my improved device electromagnetically constructed and operated, together with a diagrammatic view of a convenient form of appropriate wiring. 75

Fig. 2 shows a similar side elevation view, partly in cross-section, of my device, in which I employ compressed air to actuate 80 the moving parts of the apparatus.

Similar numerals refer to similar parts throughout the two figures.

Referring to Fig. 1, 3 indicates any suitable frame or base arranged on the car to 85 which is attached the Westinghouse type of PK controller. In order to present a full understanding of the form of apparatus used, this PK controller comprises a main control shaft 4 upon which is mounted the 90 main controller drum (not shown), the operation of which is controlled by the usual master controller, line switch and current limiting switch. The mechanism which operates the main controller drum, as shown in 95 Fig. 1, consists of a pair of cylinders 5 and 6, whose common piston rod (not shown) carries a rack 7, which engages with a pinion 8 mounted on the shaft 4. Compressed air is used to operate the cylinders 5 and 6 furnished from a suitable source of supply 100 through the inlet pipes 9 and 10 respectively. Slide valves admitting the compressed air to and from the cylinders 5 and 6

2

are controlled by the magnets 11 and 12 respectively. I have shown the form of these slide valves on the left side of Fig. 1, such valve 13, through its vertical reciprocating movement in the valve chamber 14, by the energizing and deenergizing of the magnet 11, admits compressed air to the cylinder 5 through the port 15 when the valve 13 is depressed against the coil spring 16 by such energizing of the magnet 11. 17 indicates the exhaust port for the chamber 14, when the valve 13 is moved upwardly by the spring 16, when the magnet 11 is subsequently deenergized. The cylinder 5 and magnet 11 are commonly termed the "on" cylinder and "on" magnet, while the cylinder 6 and magnet 12 are called the "off" cylinder and "off" magnet respectively.

When the "on" valve magnet 11 is energized, the valve 13 is lowered and compressed air is admitted to the "on" cylinder 5 through the inlet pipe 9, valve chamber 14 and port 15, and when the "off" valve magnet 12 is energized, air is released from the "off" cylinder 6. Therefore, when both of these magnets 11 and 12 are simultaneously energized, the main controller drum is rotated in a clockwise direction through the movement of the rack 7 toward the right, and when both magnets 11 and 12 are deenergized, the drum is moved in a counter-clockwise direction by the reverse movement of the rack 7 toward the left. If, during the clockwise movement of the drum, the "off" valve magnet 12 alone be deenergized, the rotation of the main controller drum will immediately stop. In order that this main controller drum will properly stop at the notches, an auxiliary control or interlocking drum 18 is provided, which drum has points corresponding to those of the main drum, as shown in Fig. 1, and is keyed to the extension shaft 19 of the main control shaft 4. This drum 18 is adapted to break the control circuit of the "off" valve magnet 12, and each notch is controlled by a separate control wire energized from the master controller (not shown).

My auxiliary device proper, as shown in Fig. 1, comprises a pair of solenoids 20 and 21, secured to the upper ends 22 and 23 of the cups for the valve magnets 11 and 12 respectively. As both solenoids 20 and 21 are similarly constructed and operated, a description of the solenoid 20, mounted in the cap 24 secured to the end 22 of the cup for the magnet 11, as shown in cross-section, will suffice. The core 25 is normally held in position shown in Fig. 1 by the coil spring 26, slightly above the armature 27 which is connected to, or rests upon, the upper end 28 of the slide valve 13. 29 and 30 are spring-controlled contact buttons which are preferably located at either end of the car within convenient reach of the motorman, whereby

the solenoids 20 and 21 may be energized at will through appropriate wiring shown in Fig. 1 from any suitable source of electro-motive force as the main circuit 31 through the resistance 32. It is obvious from the diagram of the wiring that the operator by making connection through either of the contact buttons 29 and 30 may directly operate the slide valves 13 to advance the main controller drum through the sliding rack 7 being moved in either direction by the action of compressed air in the cylinders 5 and 6, when, for any of the reasons I have hereinbefore mentioned, the valve magnets 11 and 12 fail to respond and the slide valves 30 31 are not actuated.

Referring to Fig. 2, I have here shown a pneumatically operated auxiliary device to accomplish the reciprocation of the slide valves 13 operable at the will of the motorman. 33 and 34 indicate a pair of cylinders mounted on the upper ends of the cups for the magnets 11 and 12 respectively. The cylinders 33 and 34 are similarly constructed and I will describe only the cylinder 33, shown in vertical cross-section secured to the cup-end 22. 35 is the reciprocating piston rod, the lower end of which is normally held slightly above the armature 27 of the magnet 11, as shown in the figure, by the spring 36 coiled about the piston rod 35, and engaging the lower head of the cylinder 33 and the piston 37, which piston normally closes the exhaust port 38 as shown. 39 and 40 indicate hand valves, preferably arranged at either end of the car, and control, by means of the piping shown, the admission of compressed air from the air-tank 41 to the cylinders 33 and 34 to move downwardly the piston rods 35, whereby the slide valves 105 13 are directly actuated to rotate the main controller drum as has been hereinbefore described, all of which will be readily understood by those skilled in this art.

My improved auxiliary device, as heretofore shown and described, enables not only the slide valves of an automatic motor control system to be directly operated at the will of the motorman, but also the "on" and "off" cylinders of a pneumatic control system may be brought into instant operation when emergencies arise, or the magnets fail to operate for any reason.

I claim as my invention:

1. An auxiliary device for motor control systems, which comprises, in combination with the valve magnets for controlling the operation of said system, manually controlled means mounted on said magnets, and operable by said motor control system, for actuating said valves at will.

2. An auxiliary device for motor control systems, which comprises, in combination with the valve magnets for controlling the operation of said system, manually con-

trolled means mounted on said magnets, and operable by said motor control system, for directly actuating said valves at will.

3. An auxiliary device for motor control

5 systems, which comprises, in combination with the valve magnets for controlling the operation of said system, manually controlled means mounted on said magnets, and operable by said motor control system to 10 reciprocate said valves at will.

4. An auxiliary device for motor control systems, which comprises, in combination with the valve magnets for controlling the operation of said system, manually controlled means mounted on said magnets, and operable by said motor control system to 15 directly reciprocate said valves at will.

15 5. An auxiliary device for motor control systems, which comprises, in combination with the valve magnets for controlling the operation of said system, manually controlled means mounted on said magnets, and operable by said motor control system, to 20 directly reciprocate said valves at will.

20 6. An auxiliary device for motor control systems, which comprises, in combination with the valve magnets for controlling the operation of said system, valve stems projecting beyond the cores of said magnets, and means, controlled by the operator, and operable by said motor control system, to 25 move said projecting ends inwardly at will.

25 7. An auxiliary device for motor control systems, which comprises in combination with the valve magnets for controlling the operation of said system, electromagnetic 30 devices connected with the main circuit to actuate said valves at will.

30 8. An auxiliary device for motor control systems, which comprises, in combination with the valve magnets for controlling the operation of said system, valve stems projecting beyond the cores of said magnets, and electromagnetic devices connected with the main circuit to directly actuate said valves at will.

35 with the valve magnets for controlling the operation of said system, electromagnetic devices connected with the main circuit to directly actuate said valves at will.

35 8. An auxiliary device for motor control systems, which comprises in combination with the valve magnets for controlling the 40 operation of said system, valve stems projecting beyond the cores of said magnets, and electromagnetic devices connected with the main circuit and controlled by the operator, to move said projecting stems inwardly 45

45 9. An auxiliary device for motor control systems, which comprises in combination with the valve magnets for controlling the operation of said system, a solenoid mounted 50 on each of said valve magnets and connected with the main circuit to actuate said valves at will.

50 10. An auxiliary device for motor control systems, which comprises, in combination 55 with the valve magnets for controlling the operation of said system, valve stems projecting beyond the cores of said magnets, and a solenoid mounted on each of said valve magnets and controlled by the operator, to move said projecting stems inwardly 60 at will.

JAMES V. GERAGHTY.
